ELECTRIC HOTPLATE OR SIMILAR ARTICLE

Jerry E. Wright, Corning, N.Y., assignor to Corning Glass Works, Corning, N.Y., a corporation of New York

Filed Oct. 20, 1960, Ser. No. 62,553

Term of patent 14 years

(Cl. D81—10)

FIG. 1 is a top plan view of an electric hot plate or similar article embodying my new design.

FIG. 2 and FIG. 4 are opposite end elevations of the same.

FIG. 3 is a front elevation of the same, the casserole dish shown in broken lines being included for illustrative purpose only.

FIG. 5 is a bottom plan view of the same.

The rear of the electric hot plate is a mirror image of the front shown as indicated in FIG. 3.

I claim:

The ornamental design for an electric hot plate or similar article as shown and described.
